(57) **CLAIM**

The ornamental design for a silicone cup lid, as shown and described.

DESCRIPTION

FIG. 1 is a top perspective view of a silicone cup lid, showing our new design positioned over the top of a cup;

FIG. 2 is a top plan view thereof;

FIG. 3 is a bottom plan view thereof;

FIG. 4 is a front elevational view thereof; and,

FIG. 5 is a back elevational view thereof.

The broken line showing of a cup in the drawings depicts unclaimed environmental subject matter; the broken lines in FIGS. 2 and 3 on the top surface of the lid depict boundaries of the claim. The broken lines form no part of the claim.
